UNITED STATES PATENT OFFICE.

ALBERT S. HOWELL, OF CHICAGO, ILLINOIS, ASSIGNOR TO BELL & HOWELL COMPANY, OF CHICAGO, ILLINOIS, A CORPORATION OF ILLINOIS.

TRIPOD-HEAD MECHANISM.

1,276,220.

Specification of Letters Patent. Patented Aug. 20, 1918.

Application filed November 27, 1916. Serial No. 133,769.

To all whom it may concern:

Be it known that I, ALBERT S. HOWELL, a citizen of the United States, and a resident of the city of Chicago, county of Cook, and

5 State of Illinois, have invented certain new and useful Improvements in Tripod-Head Mechanism, of which the following is a specification.

My invention relates to tripods for instruments of precision, such as transits for surveying, and especially apparatus relating to the art of motion pictures, and the like, and more particularly to the head of the tripod which is adapted to carry the instrument.

15 One of the objects of my invention is the provision of a tripod head that is capable of minute adjustment both in a horizontally rotary direction and a vertically rotary direction or tilttable manner. Another object 20 of my invention is the provision of a tripod head that is rotated by means of a crank and train of gears so that each revolution of the crank will move the axis of the instrument mounted thereon one degree, or, in other 25 words, 360 revolutions of the crank will completely rotate the instrument. A further object of my invention is the provision of a device of this character that is capable of being tilted to any angle of inclination,

30 and also capable of rotation when so inclined, and vice versa, both adjustments being attained by the actuation of a single crank. Still further objects of my invention are the provision of means whereby the 35 actuating handle or crank, when released by the operator, will return to a "neutral" position so that the apparatus may not be accidentally moved out of its adjusted position, and also to provide a suitable release mecha-

40 nism that is adapted to permit the release of the mechanical adjusting means contained within the head so that a coarse adjustment may be quickly made with the hands alone. I prefer to accomplish the divers objects of 45 my invention by the means and in the manner hereinafter more fully described and as more particularly pointed out in the claims, reference being had to the accompanying drawings forming a part of this specification, wherein—

50 Figure 1 is a top plan of my improved tripod head, the instrument to be supported

thereon and the legs therefor being removed for the purpose of clearness.

Fig. 2 is a vertical elevation of one side 55 of my invention.

Fig. 3 is a vertical central section taken on line 3—3 of Fig. 1 and drawn to a slightly enlarged scale.

Fig. 4 is a fragmental view looking at the 60 mechanism from the top and having the cover plate and other parts removed for the purpose of clearness.

Fig. 5 is a vertical section of the actuating gears for rotating the tripod head, the same 65 being taken on line 5—5 of Fig. 4.

Fig. 6 is a fragmentary vertical section of the upper end of the actuating crank.

Referring to the drawings, and more particularly to Figs. 2 and 3, it will be observed 70 that my improved tripod head comprises a box-like structure or housing for inclosing the actuating mechanism. This housing consists of a hollow cylindrical wall 10 that is closed at its top and bottom by means of a 75 top plate or cap 11, and a bottom plate 12, of substantially circular contour and adapted to fit said cylindrical wall snugly to exclude dust and foreign matter and be capable of rotation with reference to said cylindrical 80 wall. Extending above, and preferably integral with the plate 11, is a pair of oppositely disposed bearing lugs 13—13 that are preferably provided adjacent their upper ends with transverse screw-threaded bores, 85 into which are tapped horizontally disposed bolts 14—14. These bolts extend beyond the inner faces of these lugs and engage the depending trunnions 15—15 of a horizontally disposed plate 16. This plate 16 is suitably 90 formed to receive the base of a surveyor's transit, a telescope, a motion picture camera or any other similar instrument, the adjustment and sighting of which it is desirable to accomplish with nicety. Interposed between 95 the top plate 11 and the upper edge of the cylindrical wall 10 is a suitable annular bushing 17, of L-shape in cross-section, upon which the top plate is adapted to rest and rotate, and a graduated ring or protractor 18, having 360 graduations upon the same, is mounted immediately below said bushing 100 and retained in position by the outer extended edge of the latter. Suitable brackets

having stub extensions X, Y and Z, are provided on the exterior of the cylindrical wall 10 upon opposite sides of which stubs pivot the respective tripod legs (not shown) and 5 a spirit-level 53 is provided upon the top of plate 11.

Journaled centrally in both the top plate 11 and the bottom plate 12 is the operating or main shaft 19 of the actuating mechanism, the lower end whereof extends below the bottom plate and has a suitable crank or handle 20 secured thereto for rotating the same. The upper end of the shaft 19 is slightly reduced in diameter to form an extension 21, that extends up into a suitable, dust-proof cap 22, where it is provided with an enlarged head 23. A bushing or sleeve 24 surrounds the shaft 19 adjacent the reduced portion 21 and this bushing has 20 its bore increased at 25 and extends through the top plate 11 (as shown in Fig. 6), so as to provide a shoulder upon which a washer 26 is disposed. A coiled expansion spring 27 surrounds the extension 21 of the shaft 25 between its head 23 and the washer 26, so that when the shaft 19 is moved longitudinally or axially downward, the spring will be depressed by the head 23, or when said shaft is raised, the shoulder formed by the 30 extension will compress the spring between the washer and the head, so that when moved in either direction and then released, the shaft will return to its neutral or normal position, the object of which will be better 35 understood after the description of the mechanism has been had.

Mounted in suitable bearings in plates 11 and 12 and with its axis vertically disposed and parallel with shaft 19, is a suitable 40 shaft 28, and adjacent and parallel thereto is another shaft 29. These two shafts 28 and 29 are adapted to carry a plurality of gears in train with each other so that a considerable reduction in speed is effected 45 when the first of the train of gears is actuated by a pinion 30 fixedly mounted upon the actuating shaft 19. The lowermost gear I (Fig. 5) on shaft 28 is in mesh with a suitable annular, internal rack J that is 50 secured to the bottom plate 12 in any suitable manner, so that the same rotates therewith and is partially inclosed within a suitable L-section annular housing 31 upon the bottom plate 12, the rear or outer portion 55 of the rack J fitting snugly against the interior surface or wall of the casing 10. Immediately above gear I is the initial gear A of the train, which is preferably keyed to the downwardly extended hub of the gear B immediately above the same on said shaft 28. Gear E is mounted upon the shaft 28 and rests upon the hub of gear B and its hub is extended upwardly around the shaft 28 and is provided with a smaller gear F 45 adjacent the top of the shaft. These gears

are all loose and free to rotate upon the shaft 28, independently thereof. The uppermost gear G on shaft 29 meshes with gear F and has its hub extended downwardly to the bottom of said shaft 29, where it has 70 a smaller gear H keyed thereto, which latter gear is in mesh with gear I. Mounted loosely upon the hub of gear G is the second gear D that meshes with gear E and has its hub extended downwardly and has a larger 75 gear C keyed thereto, which latter is in mesh with gear B.

When it is desired to rotate the tripod head, the crank 20 is pulled downward until pinion 30 thereon meshes with gear A of 80 the train. In this position the handle 20 is rotated and gear A actuates gear B and the entire train is set in motion in sequence, gear C moving gear D which is in mesh with gear E; and gear F, which is secured 85 to the latter, actuates gear G, which, in turn, rotates gear H in mesh with the large gear I and consequently the rack J is rotated. This train of gears is of a reduction of 1 to 90 360, so that one complete turn of shaft 19 will move the top and bottom plates of the tripod head and mechanism carried thereby, one degree, as will be indicated by the score on a plate 32 mounted upon the top plate 11.

Secured to and depending between lugs 95 33 on the longitudinal edge of plate 16, is pivoted a screw-threaded bolt 34 that passes through an opening 35 in the top plate 11 and enters the interior of the head. The threaded portion of this bolt 34 passes 100 through the central bore of a rocking member 36, the ends whereof are pivotally mounted in suitable trunnions 37, so as to permit the tilting of said rocking member 36 during the operation of adjusting the 105 bolt 34 to divers positions. This rocking member 36 comprises an upper and a lower plate, 38 and 39, respectively, between which a suitable rotatable gear 40 is secured. This gear 40 has its hub elongated in opposite 110 directions and surrounds the screw-threaded portion of bolt 34. The upper portion of the hub is bored and interiorly threaded to engage the thread of the bolt 34 and is also provided with longitudinal slots 50, and a 115 split collar 51 surrounds the upper end of said hub which may be drawn up or tightened by the screw 52 so as to secure a desired degree of friction between the hub and the bolt 34, to keep the bolt in adjusted 120 position. The lower portion of the hub is bored out so as to clear the threads on bolt 34. Suitable anti-friction devices 42 and 43 are disposed upon opposite sides of the gear 40 so as to facilitate the rotation of 125 the latter with respect to the rocking member 36. The pinion 30 on shaft 19 is adapted to engage gear 40 when the shaft is raised, so as to throw the same in mesh, and the rotation of said shaft causes gear 40 to 130

rotate and raise or lower the bolt by its engagement with the respective members 41. This will rotate or tilt the plate 16 upon its pivotal members and consequently tilt 5 the instrument mounted thereon to the desired angle.

In order to prevent dust and foreign matter entering the casing through the bolt opening 35, I prefer to surround the upper 10 extended end of the bolt with a conical expansion spring 44 that is inclosed within a covering of suitable flexible material 45 and the upper end of this material is folded inside of the cone spring where it is clamped 15 around the bolt 34 in a suitable groove 46 formed therein, and the lower end of the material is clamped in a suitable seat 47 in the top plate 11, by means of a suitable spring ring 48. When the bolt is elevated 20 or lowered, the spring 44 will cause the elongation of the material, and when the bolt is reversed or lowered, the material will be shortened so that a dust-proof cap or bushing is formed.

25 It will be obvious that the extreme gear reduction heretofore described develops a considerable degree of power. So as to secure the interior portion of the head with respect to the cylindrical wall 10, to permit 30 of its relative movement through the gear train and also to release such connection so that the interior portion of the head may be easily manually moved for securing coarse or rapid adjustment, I have provided the 35 brake shoe 54 mounted upon the brake-arm 55, one end whereof is pivotally secured to the top plate 11 by bolt 56. Secured to the brake arm 55 and extended beyond its opposite end is a spring plate 57 and a set screw 40 58 extends through the brake-arm so that its end rests against spring 57. The end of the brake-arm is split through the bore for set screw 58 and a screw 59 is provided to draw up the split and retain set screw 58 in adjusted position. A shaft 60 is journaled in top plate 11 adjacent spring 57, and upon the lower inner end of shaft 60 is provided an arm 61 which carries a friction roller 62 on end which engages with said spring 57. 45 50 An arm 63 is provided upon the upper outer end of shaft 60 by means of which the arm 61 may be swung past center so that the roller 62 is carried out of engagement with spring plate 57, thereby releasing the brake 55 shoe from engagement with the cylindrical wall 10 and permitting the easy manual movement of the interior mechanism of the head.

What I claim is:

60 1. A tripod head comprising a leg carrying member, a plate carried thereby and rotatable about the axis thereof, a table carried by said plate and rotatable about an axis at an angle to the axis of rotation of 65 said plate, independent actuating means for

rotating said plate and said table, and an operating member capable of respective co-action with said actuating means and adapted to be maintained normally independent thereof.

70

2. A tripod head comprising a leg carrying element, a member carried thereby and rotatable about the axis thereof, a drive shaft provided with a pinion, spindles carried by said member adjacent said shaft, a plurality of gears mounted on each spindle in train with each other, and a rack actuated by said gear train and connected to said member whereby the latter is moved bodily with relation to said leg carrying element. 75

80

3. A tripod head comprising a leg carrying element, a member carried thereby and rotatable about the axis thereof, a table mounted on said member and rotatable about an axis at an angle to the axis of rotation 85 of said member, a drive shaft, a gear train deriving its motion from said shaft, means driven by said gear train whereby said member is moved bodily with relation to said leg carrying element, and devices driven by 90 said shaft independently of said gear train adapted to rotate said table.

95

4. A tripod head comprising a leg carrying element, a rotatable member carried thereby, a table supported on said member 95 and rotatable about an axis at an angle to the axis of rotation of said member, a rocking frame carried by the member, a rotatable gear on said frame and capable of axial rotation independently of said frame, and a 100 suitable device operatively connecting said table and said gear.

100

5. A tripod head comprising a leg carrying element, a rotatable member carried thereby, a table supported on said member 105 and rotatable about an axis at an angle to the axis of rotation of said member, a longitudinally pivoted transversely tiltable rocking-frame carried by said member, an internally threaded gear journaled in said frame and capable of rotation independently of its movement with said frame, and a threaded bolt engaged by said gear and one end whereof is pivotally connected to said table. 110

115

6. A tripod head comprising a leg carrying element, a rotatable member carried thereby, a table supported on said member and rotatable about an axis at an angle to the axis of rotation of said member, a longitudinally pivoted transversely tiltable rocking-frame carried by said member, an internally threaded gear journaled in said frame and capable of rotation independently of its movement with said frame, a threaded bolt 120 engaged by said gear and one end whereof is pivotally connected to said table, and a suitably driven pinion engaging said gear.

120

7. A tripod head comprising a leg carrying element, a member carried thereby and 130

41
 rotatable about the axis thereof, a table supported on said member and rotatable about an axis at an angle to the axis of rotation of said member, spindles journaled in said member, a plurality of gears mounted on each spindle in train with each other, means operatively connecting said gear train and said member whereby the same is moved bodily with relation to said leg carrying element, means for rotating said table independently of said member, and driving mechanism adapted to successively actuate said table rotating means and said member actuating mechanism.

15 8. A tripod head comprising a leg carrying element, a member carried thereby and rotatable about the axis thereof, a table supported on said member and rotatable about an axis at an angle to the axis of rotation of said member, spindles journaled in said member, a plurality of gears mounted on each spindle in train with each other, means operatively connecting said gear train and said member whereby the same is moved bodily with relation to said leg carrying element, a rocking frame carried by said member, a gear rotatable on said frame and operatively connected to said table, and common driving means adapted to successively actuate said gear train and said last mentioned gear.

9. A tripod head comprising a leg carrying element, a member carried thereby and rotatable about the axis thereof, a table supported on said member and rotatable about an axis at an angle to the axis of rotation of said member, spindles journaled in said member, a plurality of gears mounted on each spindle in train with each other, means

40
 45
 50
 55
 60
 65
 70
 75
 80

 operatively connecting said gear train and said member whereby the same is moved bodily with relation to said leg carrying element, a rocking frame carried by said member, a gear rotatable on said frame and operatively connected to said table, the hub whereof is internally threaded, a bolt pivoted pendently upon said table and engaging the threads of said gear hub, and a drive-shaft provided with a pinion adapted to successively mesh with said gear train and said last mentioned gear.

10. A panoramic tilting device, comprising a frame, a supporting platform mounted therein, a base for said frame and platform, means to rotate said frame relatively to said base, means to rotate said platform relatively to said frame, and a rotatable shaft common to said two rotation means to engage one or the other thereof and adapted to effect the corresponding rotation.

11. A panoramic tilting device, comprising a frame, a supporting platform mounted therein, a base for said frame and platform, means to rotate said frame relatively to said base about a vertical axis, means to rotate said platform relatively to said frame about a horizontal axis, and a rotatable shaft common to said two rotation means and adapted to engage one or the other thereof to effect the corresponding rotation.

Signed at Chicago, county of Cook and State of Illinois, this 16th day of November, 1916.

ALBERT S. HOWELL
